UNITED STATES PATENT OFFICE.

CLARENCE CHARLES CLAYBERG, OF DETROIT, MICHIGAN.

ENGINE.

1,342,498.

Specification of Letters Patent.

Patented June 8, 1920.

Application filed November 8, 1919. Serial No. 336,653.

To all whom it may concern:

Be it known that I, CLARENCE CHARLES CLAYBERG, a citizen of the United States, and residing at Detroit, in the county of Wayne and State of Michigan, have invented 5 a new and Improved Engine, of which the following is a specification.

This invention relates to internal combustion engines of the two-cycle type and its object is to provide an engine in which the fuel 10 gases to be burned in a working cylinder are previously partially compressed in a separate feeding cylinder whose piston is so formed that it will receive a portion of the 15 burnt gases from the working cylinder and has a receptacle for condensed fuel which will be heated by said burnt gases sufficiently to evaporate the liquid fuel.

A further object of this invention is to 20 connect adjacent ends of the compression and working cylinders with a passage normally closed by a valve which is held onto its seat by a spring whose tension and the angular relation of the cranks of the feeding 25 and working cylinders regulate the timing 30 of the compression within the working cylinder and control the operation of said valve.

Another object of this invention is to provide a passage between the compression and 35 working cylinders in the wall of the cylinder block so as to obtain a very short path which is substantially below the end of the feeding piston at the end of its working stroke.

Another object of this invention is to so 40 proportion the feeding piston and its top ring that the upper edge of this ring will extend above the lower edge of the fuel passage to the working cylinder so that the heavier portions of the fuel will be carried into the working cylinder.

Another object of this invention is to obtain 45 an engine of high efficiency, light weight and few noise producing parts, the high efficiency being obtained by the heating of a spot in the depressed top end of the feeding piston, in which spot the heavier portions of the fuel may collect and be vaporized by the heat of the burnt gases which are conducted through the piston from the 50 working cylinder.

In the accompanying drawings, Figure 1 is a vertical longitudinal section of this improved engine. Fig. 2 is a plan of the cylinder block. Fig. 3 is a bottom plan of the cylinder head. Fig. 4 is a section on the line 4-4 of Fig. 2 on a larger scale. Fig. 5 is a

central longitudinal section of a piston for one of the compression cylinders. Fig. 6 is a diagram illustrating the position of the cranks. Fig. 7 is a side elevation of an engine embodying my invention. Fig. 8 is a side elevation of the cylinder block showing the exhaust manifold.

Similar reference characters refer to like parts throughout the several views.

The engine shown in the drawings is equipped with two working cylinders 1 and two feeding cylinders 2, preferably arranged *en bloc* and it is to be understood that any number of working cylinders and an equal 60 number of compression cylinders may be employed, the type of motor being immaterial except as hereinafter set forth. Within the working cylinders are the working pistons 3 which connect to the cranks 4 by means 65 of connecting rods 5. The cranks of the working cylinders are preferably evenly spaced around the crank shaft, as are also the cranks 6 of the feeding pistons 7 which pistons are connected to the crank shaft 8 by means of the rods 9.

The cylinder block 10 is preferably formed integral with the upper portion 11 of the crank case. The lower portion 12 of the crank case is preferably provided with an oil 85 pan 13 formed with the usual oil receptacles 14 into which the fins 15 on the lower ends of the connecting rods may dip. Bearings 16 of any desired type and construction may be formed in the ends of the crank case and 90 a fly wheel 17 may be mounted on the crank shaft 8. At the opposite end of the crank shaft I prefer to mount a magneto 18, and a belt 19 may extend from the pulley 20 on the crank shaft to the pulley 21 which is connected to the fan 22 in any desired manner.

The working cylinders are constructed on the two-cycle principle and have exhaust ports 24 which are opened at the ends of the working strokes of the pistons 3. The explosive mixture is derived from the carburetor 25 and passes up through the manifold 26 to the ports 27 in the walls of the cylinders 2, the location of these ports being shown in dotted lines in Fig. 1. The explosive mixture is partially compressed in the feeding cylinder 2 by the piston 7 during its upward stroke and flows from this cylinder through a passage 28, shown in Figs. 2 and 4, and lifts the valve 29 at the end of 105 this passage and flows into the explosion chamber 30 at the upper end of the working 110 cylinder.

cylinder. This chamber 30 is preferably formed in the cylinder head 32. Normally this valve 29 is held down by means of a spring 33 which engages a small piston 34 secured to the lower end of the stem 35 of this valve.

This passage 28 begins at the edge of the feeding cylinder and is generally below the end of both pistons when they are at the 10 ends of their outer strokes. This results in a more perfect flow of the compressed fluid and renders possible the use of a very short passage. This is particularly true because the upper edge of the upper piston ring of 15 the piston 7 extends above the lower edge of this passage so that any condensed or nearly condensed fuel which may lodge at the upper edge of the top piston ring will be blown into the passage 28 by the compressed fluid 20 before the valve 29 closes. It will not, therefore, pass down into the crank case when the piston descends.

As indicated in Fig. 6, the piston 7 is about ninety degrees ahead of the piston 3, 25 although this spacing may be considerably increased. As the piston 7 descends the valve 29 will be held closed by its spring 33 and a partial vacuum will be formed within the cylinder 2. After the piston 30 has passed the port 27, fuel will rush in through the carbureter 25 and manifold 26 and through the ports 27 into this cylinder 2. At the end of this suction stroke the cylinder 2 will be substantially filled with 35 fuel which will thereupon be compressed within the cylinder 2 until the pressure is sufficient to lift the valve 29 from its seat.

At the end of the working stroke of the working piston 3, the exhaust port 24 is 40 uncovered and the burnt gases within the cylinder 1 will rush out through the port 24 until the pressure within the cylinder is reduced to substantially that of the outside air. The feeding piston 7 has at this time 45 made substantially one-half of its working stroke and shortly after the port 24 has been opened the explosive mixture will begin to flow through the passage 28 into the explosion chamber 30, to some extent forcing 50 down the remaining burnt gases in the cylinder 1. As the piston 7 is completing its feeding stroke, the piston 3 rises and will have made one-half of its compression stroke by the time that the piston 7 has reached the 55 upper end of its feeding stroke. At this instant the valve 29 seats itself and the piston 3 continues upward until it has completed its compression stroke. An electric impulse is now received from any proper 60 source of high potential current, such as the magneto 18, over a wire 36 and a spark occurs at the terminals of a spark plug 37, igniting the compressed charge within the cylinder 2 and causing the piston 3 to be 65 driven down through its working stroke.

The ordinary gasoline of commerce does not vaporize readily, and it is liable to condense within the feeding cylinder, I have, therefore, formed the head 38 of the piston 7 quite depressed as shown in Fig. 5 and 70 have provided a conduit 39 to permit a portion of the burnt gases to flow up into contact with this head 38. The cylinder is formed with a port 41, indicated in dotted lines in Fig. 1, which communicates with 75 a port 42 in the cylinder 2 by means of a small passage 43. This arched conduit 39 which extends to the head 38 may be formed integral with said head by welding or casting, as indicated in Fig. 5. At the instant 80 that the port 42 registers with the intake end of the conduit 39, its outlet end registers with the discharge port 45 in the cylinder wall. The exhaust manifold 46 not only connects to the exhaust ports 24 but 85 also preferably connects to these discharge ports 45.

This flow of very hot gas through the conduit 39 causes a small area at substantially the middle or deepest portion of the 90 head 38 of the piston 7 to become quite hot and as a result, any fuel which may become condensed within the feeding cylinder and which collects at this point will be vaporized and mix with the other fuel gases. The 95 other fuel gases will not be unduly heated and no loss of power through overheated gases will result.

The tension of the spring 33 on the valve 29, together with the angle of advance of 100 the feeding piston control the opening and closing of the valve 29. This valve should close after the fuel charge has been injected and before the working piston has moved very far in its compression stroke and the 105 angular advance of the feeding piston must therefore be at least ninety degrees. In some cases this advance may be increased up to about 120 degrees.

The usual passages 48 and 49 for the 110 circulating liquid will be provided in the walls of the cylinders and in the head 32, the passage 49 preferably connecting to a radiator.

The details of construction and proportions of parts may all be changed by those skilled in the art without departing from the spirit of my invention as set forth in the following claims.

I claim:—

1. In an internal combustion engine, the combination of feeding and working cylinders, pistons therein, a crank shaft and connecting rods between the pistons and the crank shaft, and a passage connecting said 125 cylinders and positioned to be opened by the working piston near the end of its working stroke, said feeding piston being provided with an arched conduit adapted to register with said passage connecting said 130

cylinders through which exhaust gases from the working cylinder may pass to heat the end of the feeding piston.

2. In an internal combustion engine, the combination of feeding and working cylinders, pistons therein, a crank shaft and connecting rods between the pistons and the crank shaft, and a passage connecting said cylinders and positioned to be opened by 10 the working piston near the end of its work-

ing stroke, said feeding piston being provided with an arched conduit adapted to register with said passage through which exhaust gases from the working cylinder may pass to heat the end of the feeding 15 piston, said conduit connecting at its high point to the middle of the end of the piston which is depressed to receive condensed fuel.

CLARENCE CHARLES CLAYBERG.
